UNITED STATES PATENT OFFICE.

SPENCER D. BUTLER, OF MARSHFIELD, OREGON.

FIRE-ESCAPE.

SPECIFICATION forming part of Letters Patent No. 293,627, dated February 19, 1884.

Application filed June 6, 1883. (No model.)

To all whom it may concern:

Be it known that I, SPENCER D. BUTLER, a citizen of the United States, residing at Marshfield, in the county of Coos and State of Oregon, have invented certain new and useful Improvements in Fire-Escapes, of which the following is a specification, reference being had therein to the accompanying drawings.

This invention has relation to improvements in flexible fire-escapes; and it consists in the novel construction and arrangement of a receptacle in which the flexible escape is stored when the same is not in use; and the invention further consists in the combination of various devices, whereby persons may easily and quickly make their exit from a burning building and safely descend to the ground, all as will be hereinafter more fully explained.

The annexed drawings, to which reference is made, fully illustrate my invention, in which Figure 1 represents a vertical sectional view. Fig. 2 is a plan view. Fig. 3 is a side view of the escape.

Referring to the accompanying drawings by letter, A designates a receptacle for the ladder B when the same is not in use, which receptacle may be an article of furniture—a wash-stand or the like, or a box, as shown in the drawings. In either case the same is provided with a lid or cover, a, which may be hinged thereto, if desired. Said lid is provided with a recess, b, that is closed by a door, c, on its under side, and the same is designed to receive an escape, which is used in lowering children, persons, and parcels, as will be further hereinafter explained. The box A is provided with eyebolts d at each end, through which passes a rod, e, that is secured at each end to the floor of the building, directly beneath the window, and it is of sufficient length to extend far enough to one side of the window to allow the box to be shifted to one side, out of the way of said window. To the inside of the box or receptacle one end of the flexible ladder is secured, while the opposite end is left free, and the ladder, when not in use, is stored therein in a zigzag manner, which arrangement of the same takes up very little room and admits of a very long ladder being stored in a comparatively small receptacle.

On the inner side of the box, adjoining wall and window, I provide a cushion, f, that is secured at one of its edges to the box, and serves to protect the rope, when lowering the bag, and the window-sill from injury from the 55 iron or steel ladder in case of alarm.

The letter g represents a metal plate secured to the inner side of the box, and it is provided at one end with a projection or pin, h, on which may be a pulley, if desired, and at the other end the plate is provided with a cleat, i, which arrangement is designed to be used with the escape, which consists of a strong rope, one end of which is made fast to a pad or front piece, j, which may be made as a stout 65 sack or bag, for the purpose of lowering children and valuables, the same being provided with three straps, k k k', while the opposite end of the rope is free and, when lowering the bag to the ground, passes under the pin h, thereby 70 enabling a person to lower the same with but little labor and with safety. Said straps, when the bag is applied to the body of a person, are applied in the following manner: The straps k k are to be passed around the waist and 75 brought back in opposite directions and buckled in front to the buckle k², with the bag or sack also in front, and the strap k' passes between the legs, up the back, over the person's shoulder, and buckles in front to the buckle k³. The bag is particularly serviceable 80 to lower children and valuable articles, parcels, &c., by filling the bag therewith, when the escape is not in use in lowering adults. The cleat above mentioned serves to secure 85 the rope, when lowering the bag or person, if the unused portions of said rope should become tangled, thus allowing the operator to straighten it out.

A fire-escape constructed as above described 90 is simple in operation, and the receptacle could be made ornamental, to serve as an article of furniture, and at the same time all the appliances are stored within the receptacle, and are therefore hidden from view, and if the escape 95 is placed in the top story of the building, the same can be used by persons in the lower rooms in descending, as the escape, when lowered, will pass directly in front of the lower windows, which are in line with the escape or top 100

window, and it will be observed that a fire-escape as herein set forth is cheaply manufactured, and can be placed in the room without injury to the building.

Having thus fully described my invention, what I claim, and desire to secure by Letters Patent, is—

1. In a fire-escape, the combination, with the receptacle A, constructed and arranged as described, of the inclined plate or bar g, secured to the inside of the receptacle, and provided with a pin, h, at its lower end, and the cleat i at its upper end, said cleat and pin or stud adapted to operate in connection with the rope of an escape, whereby said escape is lowered, as described.

2. In a fire-escape, the combination of the receptacle, plate g, pin h, cleat i, and escape j, having straps k k', as shown and described.

3. In a fire-escape, the escape consisting of the rope, the bag j at the end thereof having secured thereto straps k k', adapted to fasten the escape to the wearer, as shown and described.

In testimony whereof I affix my signature in presence of two witnesses.

SPENCER D. BUTLER.
